UNITED STATES PATENT OFFICE.

DANIEL A. SMITH, OF CHEVY CHASE, MARYLAND, AND CHARLES P. STIRLING, OF WASHINGTON, DISTRICT OF COLUMBIA, ASSIGNEES TO DISTRICT OF COLUMBIA PAPER MANUFACTURING COMPANY, OF WASHINGTON, DISTRICT OF COLUMBIA, A CORPORATION OF VIRGINIA.

MACHINE FOR MAKING DECORATED PAPER.

Application filed July 14, 1925. Serial No. 43,515.

The invention relates to the manufacture of printed decorated paper.

One of the objects of the invention is the production of decorative patterns or designs 5 on paper by printing and in which there will be a wide range of color multitudes and in which the decorations will be uniform in repetition of design and color intensities.

A further object of the invention relates 10 to the production of printed decorated paper, while the paper is still in the making and passing through the paper making machine.

The invention is preferably practiced by 15 employing in a paper making machine a printing attachment comprising an etched or intaglio engraved cylinder, in connection with an offset roll having a resilient surface, to which the color or ink from the etched 20 or engraved cylinder is transferred; from the transfer roll, the ink is applied to the wet paper sheet during its passage through the paper making machine.

Printing directly on calendered paper 25 from an engraved design cylinder is well known in the art. It has been found however that printing by direct contact of the wet paper sheet with an engraved design cylinder will not produce uniform or satisfactory results, but an uneven spotty deposit 30 of color, due to the roughness and unevenness of the paper sheet.

In the invention the printing contact is between the plain resilient surface of the 35 transfer roll and the wet pressed sheet, and thereby it is possible to deposit the color uniformly all over the paper sheet regardless of its rough or uneven surface.

Referring to the drawing, there are illustrated 40 diagrammatically portions of a paper making machine to which has been applied the specific printing attachment for the purpose of carrying out the invention.

The drawing shows press rolls 10 and 11, 45 which convey the felt 12 of a paper-making machine, and which carries the paper sheet 13 from the sheet forming portion of the machine. The rolls 10 and 11 constitute means for removing from the paper sheet 50 an excess of moisture. The sheet 13 passes over guide rolls 14 and 15 to the press rolls

16 and 17, from which it passes to the driers 18 and 19.

When the paper sheet passes around the press roll 17, it is brought into contact with 55 the transfer rolls 20 and 21, formed of resilient material, well known in the printing art, or surfaced with resilient material such as rubber. These transfer rolls carry the ink or color designs received from the design 60 rolls 22 and 23. The design rolls may be formed in any suitable manner, but it has been found that etched or intaglio engraved cylinders of metal produce the most satisfactory results. It will be understood that the 65 rolls 22 and 23 are formed with depressions constituting pockets for the reception of ink or color in just sufficient quantity to produce the required effects upon the paper, and that these depressions vary in depth.

Ink or water color 24 is supplied to the 70 design rolls and wiped by the doctors 25 and 26, as is usual in intaglio printing machines. It has been found that water colors or water inks can be successfully used with 75 this invention. The sheet being wet has a tendency to absorb water color readily, producing very soft and striking effects.

An accurate control of the color supply is obtained by the extent of the depressions in 80 the intaglio cylinder and by the variations in the depth thereof. The depth of the depressions controls the quantity of color. The contact between the metal design cylinder and the resilient surface of the transfer roll 85 produces a complete transference of the color to the transfer roll and at the same time a slight spreading or distribution of the color upon the transfer roll. When the transfer roll comes into contact with the wet 90 paper, the color is completely absorbed by the paper, the two surfaces being jointly sufficiently resilient and compressible to cause contact to be established at every point and all of the color to be transferred from 95 the plain resilient surface of the transfer roll to the wet paper sheet. The wet condition of the paper insures complete absorption of the color by the paper. In this second transfer of color, there is a further 100 slight spreading or distribution of the color.

What is claimed is:

1. A machine for producing decorated paper comprising in combination, a paper making machine and a printing attachment therefor, the printing attachment consisting of an intaglio printing press incorporating an engraved metal design cylinder and an offset roll, the printing attachment being inserted in the paper making machine in advance of the final drying rolls.
- 10 2. A machine for producing decorated paper, in combination with a paper making machine comprising means for forming a sheet and removing the excess water therefrom, and drying rolls, of a printing attachment comprising an engraved metal design cylinder and a resilient offset roll, the said attachment being located between the means for removing the excess water and the drying rolls.
- 15 3. A machine for producing decorated paper, in combination with a paper making machine comprising means for forming a sheet and removing the excess water therefrom, drying rolls, and press rolls in advance of the drying rolls, of a printing attachment comprising an engraved metal design roll and a resilient offset roll, mounted adjacent to the said press rolls, the said offset roll pressing against the paper sheet as it passes around the said press roll.

In testimony whereof we affix our signatures.

DANIEL A. SMITH.
CHARLES P. STIRLING.
